UNITED STATES PATENT OFFICE.

CHARLES W. BRUSH, OF BATH, NEW YORK, ASSIGNOR OF ONE-HALF TO THOMAS SHANNON, OF BATH, NEW YORK.

ROTARY EXPLOSIVE-MOTOR.

1,186,879.

Specification of Letters Patent. Patented June 13, 1916.

Application filed January 13, 1916. Serial No. 71,912.

To all whom it may concern:

Be it known that I, CHARLES W. BRUSH, a citizen of the United States, residing at Bath, in the county of Steuben and State 5 of New York, have invented certain new and useful Improvements in Rotary Explosive-Motors, of which the following is a specification.

This invention relates to certain new and 10 useful improvements in rotary explosive motors.

The primary object of the invention is the provision of a rotary motor which is cheap and easy to manufacture, being 15 formed of but few parts and possessing great strength and efficiency, the motive power being an explosive mixture ignited after the manner of the usual gasoline engine.

A further object of the device is the provision of a rotary explosive motor so arranged as to impart a large number, such as twelve, forcible impulses to the motor shaft during each revolution thereof, the frequency of the explosions of the motor approximating a continuous application of 25 force to the shaft whereby the smooth running of the motor is effected, minimizing any pulsating effects upon the motor shaft which are sometimes present in this class of 30 engines.

A still further object is the provision of a gasoline engine of the rotary type especially adapted for employment with aeroplanes and motor vehicles and being simpler 35 in construction and more powerful in operation than the usual explosive motor of the same size and weight, the same being arranged with an efficient water cooling device.

The present internal combustion motor of 40 the rotary type contemplates the employment of an explosive mixture which has been placed under pressure exteriorly of the motor and is conducted to the explosion chamber thereof at accurately timed intervals and adapted for ignition for effecting 45 an explosion operating upon the adjacent piston head of the motor, the forward movement of such head operating to exhaust the products of a previous explosion in advance of the head outwardly of an open side port of the cylinder.

With these general objects in view and others that will appear as the nature of the invention is better understood, the same 55 consists in the novel construction, combination and arrangement of parts hereinafter

more fully described, illustrated in the accompanying drawings, and then claimed.

In the drawings forming a part of this application and in which like designating characters refer to corresponding parts throughout the several views:—Figure 1 is a side elevation of the present invention with the wire and pipe connections removed. Fig. 2 is a vertical substantially central longitudinal sectional view thereof with the inner face of the base portion shown partially in elevation. Fig. 3 is a central radial sectional view taken upon line III—III of Fig. 1 and with a portion of the casing shown in elevation, with two of the abutment valves shown in their normally closed positions. Fig. 4 is a view similar to Fig. 3 but with the abutment valves in their open positions under the influence of the rotor cams. Fig. 5 is an enlarged detail sectional view through a portion of the motor casing, with the abutment valves closed. Fig. 6 is a perspective view of a pair of the abutment valves removed from the motor. Fig. 7 is a perspective view of a portion of the rotor with one of the pistons and pair of cams carried thereby. Figs. 8 and 9 are edge views of the same in different relative positions. Fig. 10 is a perspective view of a portion of one of the side sections of the casing, and, Fig. 11 is a perspective view of the lever arm detached for one of the abutment valves.

A single motor of the present device being herein illustrated, the same will now be specifically described, it being understood however, that the same is capable of employment as a unit and a battery of any desired number of units may be installed for actuating a single power shaft, the plurality of units being also formed with a single motor casing if desired.

A motor casing is provided consisting of oppositely formed cylindrical side sections 100 10 and 11 having base portions 12 and 13 respectively, the said sections and base portions being adapted to be positioned together and secured in their engine casing formation by means of a plurality of bolts 105 14 removably secured through radially projecting lugs 15 carried by the said sections. The power shaft 16 of the motor is journaled centrally through the casing sections 10 and 11 and is preferably provided with a 110 fly wheel 17 adjacent each of the opposite sides of the casing. A disk form of rotor

18 is keyed as at 19' for revolving with the shaft 16, being arranged between the adjacent inner circular faces 19 of the casing sections. A plurality of pistons 20 of cylindrical form are arranged upon the periphery of the rotor 18 being adapted for movement in an arcuate path through a circular piston chamber 21 formed in the said section faces 19.

- 10 Abutment operating cams 22 of wedge-shaped formation are arranged in pairs upon opposite sides of the rotor 18 and adjacent and inwardly of each of the pistons 20 while an annular receiving groove 23 is 15 provided in each of the section faces 19 for accommodating the cams 22 during the operative movements of the rotor 18, it being understood that the cams 22 as well as the pistons 20 are slightly arcuate upon 20 their longitudinal axial lines and that while the cams 22 freely move without friction through the grooves 23, the pistons 20 are provided with packing rings 24 for maintaining the pistons substantially fluid-tight 25 within the chamber 21 after the usual manner of engine structures.

Combined valve and abutment members 25 and 26 are provided, being arranged in pairs oppositely positioned at desirable 30 points within the motor casing and herein shown at four different points, it being noted that an arrangement of four abutments and valves is preferable in connection with an arrangement of three of the pistons 20 such as herein shown. The abutment valves 25 and 26 are provided with complementally formed inner ends, being an arrangement of plug 27 and recess or socket 28 respectively, the said abutment valves being positioned 35 transversely of the piston chamber 21 arranged for sliding movement within inwardly opening sockets 29 of the casing sections. The outer ends of the sockets 29 are closed by means of dome-shaped bosses 30 forming protuberances at opposite points 40 upon the motor casing while expansion springs 31 are arranged within the sockets 29 for normally maintaining the abutment valves in their closed engagement with each 45 other and with the chamber 21 closed in a 50 fluid-tight joint, thus normally dividing the piston chamber 21 into four equal sized explosion chambers.

Each of the explosion chamber portions 55 of the piston chamber 21 is provided with an open obliquely arranged outlet or exhaust port 32 arranged adjacent the forward abutment of such chamber section and with an ignition device such as a spark plug 33 60 at a point adjacent the abutment at the rear end of such explosion chamber, it being understood that the pistons 20 move in the direction of the arrow shown in Fig. 2 when the motor is in operation.

65 Each of the abutment valves 25 and 26

is provided with a lever arm 34 having one slightly enlarged end 35 and swingingly mounted within opposite grooves 36 in the section faces 19 by means of retaining straps 37 engaging over the said arm ends 35. The 70 opposite flat end 38 of each of the lever arms 34 is slidably positioned within a side slot 39 of the adjacent abutment valve and whereby as will be evident, any shifting movement of the lever arm 34 occurs simultaneously with the longitudinal sliding movements of the abutment valve attached thereto.

The aforementioned springs 31 normally retain the abutment valves closed as shown 80 in Figs. 3 and 5 of the drawings and at which times, the opposite intermediate bowed out surface 40 of the lever arms is positioned within the path of movement of the pairs of cams 22 upon the rotor 18. It 85 will thus be evident that during the revolution of the rotor 18, the inclined forward faces 41 of the cams 22 will engage the bowed portions 40 of the lever arms 34, thus swinging the said arms outwardly and 90 separating the abutment valves 25 and 26 and arranging the same out of engagement with each other. The continued movement of the cams 22 retains the abutment valves separated to their fullest extent until the 95 cams have passed the lever arms 34 and being disconnected therefrom, the springs 31 force the abutment valves inwardly to their normally closed abutment forming position transversely of the piston chamber.

The abutment valves 25 and 26 are each provided with a similar annular recess 42 and a conduit or passage 43 for the explosive mixture is arranged substantially axially through the abutment valve member 105 opening at one end in the annular recess 42 and at its other end substantially centrally of the abutting inner end of the member. An inlet pipe 44 is tapped into each of the valve sockets 29 extending obliquely through 110 the bosses 30 of the motor casing and having an annular supply pipe 45 attached to the outer ends thereof and whereby a desirable explosive mixture may be supplied through a conduit 46, it being understood that such mixture is provided in the conduit 46 under 115 an extremely high pressure and obviating the necessity of being further compressed within the piston chamber 21. The spark plugs 33 are provided with lead wires 47 120 whereby an electric current from any desired source of energy such as a battery or a magneto may be supplied to the plugs 36 and any suitable timing device for regulating the operation of each of the plugs 33 125 with respect to the position of the adjacent piston 20 may be employed with the present motor after the manner of the timing devices upon the ordinary gasoline engine. A gear such as 48 may be arranged upon the 130

motor shaft 16 and by means of which a water circulating pump, an electric magneto or a compressor for the combustion fluid may be operated.

- 5 The casing sections 10 and 11 are provided with communicating passages or water chambers 49 arranged therein which may be filled with water or other cooling fluid and circulated if desired, pipe connections 10 50 being arranged in the motor casing sections communicating with the water chambers. The annular portions of the section faces 19 positioned outwardly of the chamber 21 are arranged with coöperating tongue 15 and groove members 51 providing a more secure engaging connection between the casing sections 10 and 11. When the casing sections are secured together by means of the bolts 14 and with the operating elements herein described in their proper positions, a transverse tie rod 52 is secured through the base members 12 and 13 of the casing sections 10 and 11, the said sections thereby forming a base for the motor positionable upon a permanent support such as 20 the ground or floor 53.

From this detailed description of the device, it will be understood that the rotor 18 and its pistons 20 may be initially started 30 to revolve by a slight turn given to either of the fly-wheels 17 of the motor shaft 16. The movement of each of the pistons 20 together with the adjacent cams 22 is identical, it being seen that when the inclined 35 forward end 41 of one of the cams 22 engages a lever arm 34, the said arm will be swung outwardly, thus forcing the abutment valve which is carried thereby outwardly and bringing the annular recess 42 of such valve in communication with the adjacent fluid supply pipe 44 and whereby the explosive mixture under pressure is admitted through the conduit 43 of the said 40 valve to a point centrally of the inner face of the latter, the mixture thus being brought in substantial contact with the side face of the adjacently positioned piston 20 until the piston faces the open inner end of such passage. The admission pipes 44 are open during 45 the entire sliding movement of the abutment valves and also during the time when such valves are at the extreme outward limit of their movement. The explosive mixture is thus admitted under pressure within 50 the passages 43 and in the rear of the nearest piston 20 when the said piston has passed the longitudinal center of the abutment valve, this occurring while the rear ends of the adjacent cams 22 are in contact 55 with the operating lever arms 34 rearwardly of the piston and also during the later closing operation of the valve. This disengagement of the cams 22 with the said lever arms 34 allows the abutment valves 25 and 26 to 60 close into their engagement with each other,

thus closing the fluid inlet pipes 44 and trapping a quantity of the compressed explosive mixture between the piston 20 and forwardly in the chamber 21, imparting a revolving impulse to the rotor 18 and the 70 shaft 16. The timing of the spark is readily effected for the plugs 33 so as to occur at each plug at a proper time after each piston 20 passes the pair of abutment valves arranged adjacent the said plug, and thus 75 each plug will be fired three times upon each revolution of the rotor 18 and shaft 16 or in other words, each of the four spark plugs 33 will explode a charge of the combustion fluid at the proper adjacent positioning of 80 each of the three pistons 20 so that twelve operative explosions will occur and a like number of successive impulses will be imparted to the rotor 18 and shaft 26 during 85 each revolution thereof.

While the form of the invention herein shown and described is what is believed to be the preferred embodiment thereof, it is nevertheless to be understood that various forms, modifications and arrangements of the 90 parts may be made without departing from the spirit and scope of the invention as claimed.

What I claim as new is:—

1. A rotary explosive motor comprising 95 opposite cylindrical casing sections detachably secured together and having spaced opposite inner faces provided with inter-engaging tongue and groove connections adjacent their outer periphery and with a 100 concentric annular piston chamber and receiving groove, a power shaft centrally journaled through the said casing sections, a disk-shaped rotor keyed to the said shaft and movably positioned between the said 105 section faces, a plurality of cylindrical pistons peripherally carried by the said rotor and movably positioned within the said chamber, a pair of wedge-shaped cams oppositely positioned upon the said rotor inwardly of each of the said pistons, and combined fluid inlet valves and abutments operatively positioned adjacent the said 110 piston chamber.

2. A rotary explosive motor comprising 115 opposite cylindrical casing sections detachably secured together and having spaced opposed inner faces provided with inter-engaging tongue and groove connections adjacent their outer periphery and with a 120 concentric annular piston chamber and receiving groove, a power shaft centrally journaled through the said casing sections, a disk-shaped rotor keyed to the said shaft and movably positioned between the said 125 section faces, a plurality of cylindrical pistons peripherally carried by the said rotor and movably positioned within the said chamber, a pair of wedge-shaped cams oppositely positioned upon the said rotor in- 130

- wardly of each of the said pistons, the said sections being provided with pairs of alining sockets spaced apart at opposite sides of the said piston chamber and with radially-extending grooves inwardly thereof, cylindrical abutment valves slidably positioned within the said sockets and having complementally formed abutting inner faces and each being provided with an axially arranged fluid conduit communicating with an annular recess of the said member, a combustion fluid admission pipe extending into each of the said valve sockets, a lever arm pivoted in each of the said radial grooves in operative connection with the adjacent abutment valve and normally positioned within the path of travel of the said rotor cams, and return closing springs for the said abutment valves.
3. A rotary motor comprising a casing having an annular piston chamber therein and being further provided with oppositely-arranged annular grooves concentrically positioned inwardly of the said chamber, a rotor revolvably mounted within the said casing, peripherally carried pistons upon the said rotor arranged within the said chamber, oppositely positioned cams upon the rotor inwardly of the said pistons positioned within the said grooves, combined fluid inlet valves and abutments operatively arranged in the paths of movement of the said cams and arranged in pairs adjacent the opposite sides of the said chamber, and a spark plug carried by the said chamber adjacent each of the said pairs of abutment valves, the said casing being provided with outlet exhaust ports communicating with the said piston chamber intermediate each pair of abutment valves.
4. A rotary motor comprising a casing having an annular piston chamber therein and being further provided with oppositely-arranged annular grooves, a rotor revolvably mounted within the said casing, pistons upon the said rotor arranged within the said chamber, oppositely positioned cams upon the rotor positioned within the said grooves, pairs of abutment valves for the said chamber, and a spark plug within the said chamber adjacent each of the said pairs of abutment valves, the said casing being provided with outlet exhaust ports communicating with the said piston chamber intermediate each pair of abutment valves.
5. A rotary motor comprising a casing having an annular piston chamber therein and being further provided with oppositely-arranged annular grooves concentrically positioned inwardly of the said chamber, a rotor revolvably mounted within the said casing, peripherally carried pistons upon the said rotor arranged within the said chamber, oppositely positioned cams upon the rotor inwardly of the said chamber, a lever, oppositely positioned cams upon the rotor inwardly of the said pistons positioned within the said grooves, oppositely positioned pivoted lever arms carried by the said casing, cylindrical abutments shiftably connected to the said arms and having complementally formed adjacent inner faces and being arranged with fluid conduits therethrough, fluid admission pipes extending through the said casing adjacent the path of travel of the said abutments and in regulated communication with the fluid conduits thereof, the said arms being arranged with inwardly projecting portions arranged in the path of movement of the said rotor cams.
6. A rotary engine comprising a motor casing having an annular piston chamber therein and provided with radially inwardly-extending grooves communicating with the said chamber and also having opposite outwardly-extending sockets communicating with the said chamber and grooves, ported abutment valves having complementally formed inner faces shiftably positioned within said sockets, closing springs engaging the outer ends of the said valves, lever arms pivoted adjacent the inner ends of the said grooves and operatively slidably attached to the said valves at the outer ends of the said arms, fluid conducting pipes tapped into the said sockets, and operating means for the said lever arms.
7. A rotary engine comprising a motor casing having an annular piston chamber therein and provided with radially inwardly-extending grooves communicating with the said chamber and also having opposite outwardly-extending sockets communicating with the said chamber and grooves, ported abutment valves having complementally formed inner faces shiftably positioned within said sockets, closing springs engaging the outer ends of the said valves, lever arms pivoted adjacent the inner ends of the said grooves and operatively slidably attached to the said valves at the outer ends of the said arms, fluid conducting pipes tapped into the said sockets, a rotor revolvably mounted within the said casing, a piston peripherally carried by the said rotor and arranged within the said chamber, and cams carried by the opposite sides of the rotor and having forward inclined ends and having a path of travel transversely of the path of travel of the said lever arms and in the same plane as the said arms when in their normal positions with the said valves in their closed abutment forming arrangement.
- In testimony whereof I affix my signature.
- CHARLES W. BRUSH.
